UNITED STATES PATENT OFFICE.

WILLIAM C. BROWN, OF NEW YORK, N. Y., ASSIGNOR TO HENRY R. WORTHINGTON, OF NEW YORK, N. Y., A CORPORATION OF NEW JERSEY.

VALVE-MOVEMENT FOR STEAM-ENGINES.

SPECIFICATION forming part of Letters Patent No. 746,667, dated December 15, 1903.

Application filed April 22, 1903. Serial No. 153,725. (No model.)

To all whom it may concern:

Be it known that I, WILLIAM C. BROWN, a citizen of the United States, residing in the borough of Richmond, city of New York, county of Richmond, and State of New York, have invented certain new and useful Improvements in Valve-Movements for Steam-Engines, fully described and represented in the following specification and the accompanying drawings, forming a part of the same.

The especial object of the present invention is to provide an improved valve-movement for multiple-expansion duplex engines by which the length of the engine may be reduced, a short cut-off link for the high-pressure cylinder be permitted, and the use of cross-heads on the piston-rods for operating the valve-movement be avoided.

The invention is intended especially for vertical engines, but may also be used for horizontal engines in cases where the results attained by the invention are desired.

In the preferred construction embodying the invention I attain the desired results in a triple or quadruple expansion engine by mounting the crossover rock-shafts and levers of a duplex valve-movement between the high and intermediate pressure cylinders and operating the rock-shaft levers by rods from the low-pressure pistons instead of from cross-heads on the piston-rods.

While the invention is especially designed for triple-expansion engines and certain important results are attained therein which are not secured in compound engines, the invention includes also a similar arrangement in engines not having the high-pressure cylinder outside the crossover-shafts, in which construction I preferably place the crossover-shafts at the end of the engine.

For a full understanding of the invention a detailed description of constructions embodying the features of the invention in the preferred forms will now be given in connection with the accompanying drawings, forming a part of this specification, and the features forming the invention will then be specifically pointed out in the claims.

In the drawings, Figure 1 is a side elevation of the steam end of a vertical triple-ex-

pansion duplex engine. Fig. 2 is a front elevation of the same with one of the low-pressure cylinders partly sectioned to show the construction. Figs. 3 and 4 are views similar to Figs. 1 and 2, showing a compound engine embodying the broader features of the invention.

Referring now especially to Figs. 1 and 2, A B C are the high, intermediate, and low pressure cylinders on one side of the engine, and A' B' C' the corresponding cylinders on the opposite side of the engine, the high-pressure cylinders exhausting through pipes D into receiver E, from which the intermediate pressure cylinders take steam through pipes F and exhaust in turn through pipes G into receiver H, from which the low-pressure cylinders take steam through pipes I, exhausting through pipe J. Any suitable valve construction may be used for controlling the admission and exhaust of steam, employing either separate cut-off valves or combined admission and cut-off valves, and cut-off valves may or may not be used on the intermediate pressure cylinders, as preferred.

In the construction shown cut-off valves are used only on the high-pressure cylinder, and separate cut-off valves are employed, the admission-valves on the three cylinders being shown as operated by cranks 10 on the valve-stems connected together and to the crossover rock-shafts by links 11, and the high-pressure cut-off valves are operated by cranks 12 and links 13 from levers 14, which are connected by links 15 to the crossover-shafts. All the parts above described may be of any other usual or suitable form.

Referring now to the features of construction in which the invention is especially embodied, the high-pressure and intermediate-pressure cylinders are separated sufficiently to permit the crossover rock-shafts of the valve-movement to be mounted between them. These cross-over rock-shafts K L are mounted in brackets 16 on the supports 20 of the high-pressure cylinders and are provided with the usual cranks 1 at their opposite ends, to which the links 11 are connected for operating the admission-valves, and with the cranks 2, to which the links 15 are connected for operating the high-pressure cut-

off valves, so that the admission-valves on each side are operated from the opposite side of the engine and the cut-off valves from their own side, as usual in this class of engines, and the rock-shafts K L are also provided with the usual levers 17 for operating the rock-shafts. These levers 17, however, instead of swinging in line with the cylinders and being operated by cross-heads on the piston-rods, as usual in duplex engines, are mounted between supports 20, which support the high-pressure cylinders and are operated from rods M, which enter the low-pressure cylinders and are connected to the low-pressure pistons N, these rods M operating the levers 17 through links 18 connected to studs 3 on the rods M and to the ends of the levers 17.

The construction shown in Figs. 3 and 4 is substantially the same as shown in Figs. 1 and 2 except that the engine is a compound engine, so that the third cylinders A A' are omitted. The arrangement of the crossover-shafts and means for operating them are the same as in Figs. 1 and 2, the brackets 16 for the crossover-shafts being mounted on supports 21 on the top of the high-pressure cylinders B B'. The same letters of reference are used for corresponding parts in the construction shown in Figs. 3 and 4, and the previous description will apply to this construction also.

While no cut-off valves are shown on the cylinders B B' in either of the constructions illustrated, it will be obvious that such cut-off valves, if used, will be operated from the crossover-shafts through direct and short connections, as in the case of the cut-off valves of the cylinders A A'.

It will be understood that modifications may be made in the construction, arrangement, and position of the rock-shafts and means for operating them without departing from the invention, and I am not to be limited to the exact construction shown. Thus while I preferably mount the rock-shafts in the position shown for economy of space, convenience, and equalization of the length of the links the invention, considered broadly, includes constructions in which the rock-shafts are mounted in any other position along or between or at the end of any of the cylinders.

What is claimed is—

1. In an expansion duplex engine having two or more cylinders on each side, the combination with the valves, of rock-shafts extending across the engine and connected to the valves for operating the valves on each side of the engine from the opposite side, rock-shaft-operating rods carried by the pistons of the larger cylinders, and connections between said rods and the rock-shafts.

2. In an expansion duplex engine, the combination with the cylinders on opposite sides of the engines and their valves, of rock-shafts mounted between the high-pressure cylinder and the next cylinder and extending across the engine and connected to the valves for operating the valves on each side of the engine from the opposite side, rock-shaft-operating rods carried by the low-pressure pistons, and connections between said rods and the rock-shafts. 65 70

3. In a triple-expansion duplex engine, the combination with the cylinders on opposite sides of the engine and their valves, of rock-shafts mounted between the high and intermediate pressure cylinders and extending across the engine and connected to the valves for operating the valves on each side of the engine from the opposite side, rock-shaft-operating rods connected to the low-pressure pistons, and connections between said rods and the rock-shafts. 75 80 85

4. In a triple-expansion duplex engine, the combination with the cylinders on opposite sides of the engine and their valves, of rock-shafts mounted between the high and intermediate pressure cylinders and extending across the engine and connected to the valves for operating the valves on each side of the engine from the opposite side for admission and operating the high-pressure cylinder-valves by their own side for cut-off, rock-shaft-operating rods connected to the low-pressure pistons, and connections between said rods and the rock-shafts. 90 95

5. The combination with the cylinders B, C, and B', C', on opposite sides of the engine, and their valves, of rock-shafts K, L mounted outside the smaller cylinders B, B' and connected to the valves, rods M carried by the pistons N of the larger cylinders C, C' and extending between the cylinders B, B', and connections from the rods M to the rock-shafts K, L between the cylinders B, B', substantially as described. 100 105

6. The combination with the high, intermediate and low pressure cylinders A, B, C, and A', B', C', on opposite sides of the engine, and their valves, of rock-shafts K, L mounted between the cylinders A, A' and B, B' and connected to the valves, rods M carried by the low-pressure pistons N, and connections from the rods M to the rock-shafts K, L, between the cylinders B, B', substantially as described. 110 115

In testimony whereof I have hereunto set my hand in the presence of two subscribing witnesses. 120
